UNITED STATES PATENT OFFICE.

CARL F. BUSCHNER, OF NEW YORK, N. Y.

DESIGN FOR A PLUSH BALL.

SPECIFICATION forming part of Design No. 23,547, dated August 7, 1894.

Application filed July 12, 1894. Serial No. 517,378. Term of patent 7 years.

To all whom it may concern:

Be it known that I, CARL F. BUSCHNER, a citizen of the United States, residing at New York, in the county and State of New York, 5 have invented and produced a new and original Design for Plush Balls, of which the following is a specification, reference being had to the accompanying drawing, forming a part thereof.

10 The drawing represents a perspective view of a plush ball showing my design.

The leading feature of my design consists of a plush ball provided with a series of outwardly projecting radial tufts.

a, is a plush ball provided with the outwardly projecting radial tufts *b*, composed of longer threads than the body of the ball. *c* is the suspending loop secured to the ball.

What I claim is—

The design for a plush ball as herein shown 20 and described.

CARL F. BUSCHNER.
